SLEEVE CONSTRUCTION

Edna Berger Fried, Forest Hills, New York, N. Y.,
assignor to Adler & Adler, Inc., New York, N. Y.,
a corporation

Application January 26, 1946, Serial No. 643,506

5 Claims. (Cl. 2—125)

1

This invention relates to garments and more particularly to the sleeve and underarm construction thereof.

In the construction of garments suitable for work, play or sportswear it is important that the greatest possible freedom of the arm, shoulder and back movement is provided.

In the conventional garments frequently gussets are inserted of additional material which gussets are inserted in between the sleeve edges and adjacent to armhole seam, thereby substantially adding at the underarm pit room for the movement of the arm and preventing thereby the pull on the body of the garment when the arms of the wearer are in raised position.

Another conventional method employed provides for tucks and gathers which provide for the desired fullness to give the required freedom of movement for garments of the herein referred to type.

The employment of these conventional methods of construction for garments generally known as of the sport or work type cause bulges, gaps and folds of unsightly appearance when the wearer's arm is in raised position.

The inserted gussets frequently rip under strain or pull during exercise or work.

In laundering or repressing of the garments difficulties are entailed to obtain a smooth press which will give the garment crispness and newness in effect.

An object of my invention is to provide a sleeve and underarm construction which will obviate the herein recited disadvantages.

Another object of this invention is to provide a sleeve construction suitable for garments of the sport or work type in which the greatest possible freedom of the arm, shoulder and back is provided.

Another object of my invention is to provide an underarm construction, neat in appearance, and which will do away with customary folds, bulges, tucks or gathers heretofore occurring, and heretofore provided for underarm fullness.

Another object of my invention is to construct a more durable underarm and sleeve construction easy of manufacture with predetermined dimensional accuracy by faithful adherence to the accurate measurements of the form of the wearer.

A further object of my invention is to do away with a number of marginal seams in the garment and to distribute the strain of action equally on front, back and sleeve and armhole.

These and other objects and purposes of the

2

invention will become apparent as the description thereof proceeds.

Referring to the drawings:

Fig. 1 is a garment showing the conventional sleeve member and having a conventional gusset inserted in between;

Fig. 2 is a garment showing the conventional sleeve member with tucked or gathered fullness at armhole portion of said garment;

Fig. 3 is a front view of a garment embodying my invention;

Fig. 4 is a rear view of the garment shown in Fig. 3;

Fig. 5 is a cross-sectional view of the sleeve construction of the garment shown in Figs. 3 and 4 taken on the line A—A of Fig. 3;

Fig. 6 is a view of the pattern of blank from which the sleeve shown in the garment of Figs. 3 and 4 is made;

Fig. 7 is a view of the pattern blank for the front of the garment shown in Figs. 3 and 4;

Fig. 8 is a view of the pattern blank for the rear of the garment shown in Figs. 3 and 4;

Fig. 9 is a front view of another garment embodying my invention;

Fig. 10 is a rear view of the garment shown in Fig. 9;

Fig. 11 is a pattern blank or sloper, the full lines of which is similar to the front of the garment shown in Figs. 9 and 10, except that it is in one piece;

Fig. 12 is a pattern blank, the full lines of which show the back sloper of the garment as shown in Figs. 9 and 10;

Fig. 13 is a sleeve pattern blank, the full lines of which show the sleeve sloper or a pattern blank of the garment as shown in Figs. 9 and 10 and embodying my invention;

Fig. 14 is a view of a blank having a lateral right angle extension coordinate with armhole curve rear member shown in Fig. 15; and

Fig. 15 is a view of a back member blank having a normal symmetrical armhole to coordinate with armhole of the front member shown in Fig. 14.

In the construction of the garment embodying my invention a conformingly proportionate relation between the armhole and side edge portions of the sleeve blank member of the garment and the edge portions of the front and back blank members of the garment must be maintained. In Figs. 7 and 8 are shown the respective front and back blank members of my garment, and Fig. 8 shows my blank member is of the normal symmetrical type.

The lower armhole $K'E^4F^1$ of the front blank member, Fig. 7, is dropped below the armpit E continuing the concave curved armhole portion thereof below the armpit E^4 to F^1 , the concave portion E^4F^1 forming thereby an enlarged concave armhole space which is for the reception of the rectangular lateral edge of the sleeve blank member G of the garment.

In the construction of the garment embodying my invention, I am not limited to the type, style or design of a garment. The garment may be of any type. It may have shoulder portions adapted to be joined together. It may have panels such as are shown in Figs. 3 and 4 or Figs. 9 and 10. The sleeve blanks or slopers may be long or short. The sleeve blanks may also be of several pieces, cut up but adaptable for joining together. Care, however, must be taken that the several pieces be so dimensioned that in the assembled and joined together position the entire unit of the assembled and joined together pieces be within the dimensions of the perimeter of the herein illustrated and described pattern blank members, wherein the relation and association of the several blanks are designed and intended to embody the features of my invention.

The sleeve blank G is cut with a straight edge BD which is at right angles to the sleeve edge BC also of a straight edge. The edge BC forms the wrist portion of the sleeve. The sleeve edge opposite to wrist edge BC of the sleeve blank is convexly curved and this forms the head of the sleeve $FUED$, which head is joined to the armhole portion LM or shoulder end portion of the garment at edges KE^4 of the front and rear blanks LM .

The straight side edge DB has an opposite side CPR which opposite side is extended by a substantially rectangular lateral extension $FURP$. This extension provides material in addition to the normal symmetrical sleeve G .

Care must be taken that this extended lateral portion of the sleeve conforms in dimensional proportion to the perimeter of the concavely shaped armhole portion of the front member of the garment; said front member Y , which has been herein shown, has a longer and more hollow armhole edge KE^4F^1 than the normal symmetrical armhole of the back member W of the garment.

The extended sleeve edge portion $FURP$ is concavely and gradually curved near the wrist end thereof. The side opposite to BC forms the head DEU .

The straight intermediate side FR (Fig. 6) connects the ends of the extensions; and the concavely curved edge RPC is secured to the straight side DB forming thereby the tubular sleeve.

The intermediate side FR of the sleeve is secured to the upper part of the side MZ ; Fig. 8, of the edge portion of the back. The remaining end of the extension and the shoulder end or head of the sleeve is secured to the armhole curves of the front and back portions (Figs. 7 and 8).

As will be seen by the illustration and description herein, there must be observed careful conformity in the relation of the several pattern blanks used in the construction of the garment embodying my invention.

Obviously, the invention admits of various modifications. For instance, the process lends itself to a garment illustrated in Figs. 9 and 10, wherein my method is used in transverse rela-

tion. Fig. 9 illustrates the front of another garment embodying my invention.

In the herein illustrated garment the under-arm fullness is formed by the manipulation of the front and back pattern blanks, and by the conforming coordinating manipulation of the sleeve pattern blank in transverse relation to the process shown and described of the garment illustrated in Figs. 3 and 4.

10 Referring to Fig. 11, the full lines show the perimeter of the blank shown in Fig. 9. The dotted lines adjacent to the full lines of Fig. 11 illustrate the difference in the perimeter when compared to the normal symmetrical blank of a garment. It will be seen therefrom that I extend the blanks at armpits K' and L' by adding substantially triangular lateral extensions N , said extensions beginning from about the armpit and continuing by concave tapering so as to blend gradually with the remaining side edges of the blank.

The back pattern blank member, Fig. 12, has also a substantially triangular lateral extension N which tapers in a manner as to blend with the side edges of said back blank.

The dotted lines in the drawing, Fig. 12, are to illustrate the difference between my new back and the normal symmetrical back blank pattern.

Referring to Fig. 13, which illustrates the 30 sleeve pattern blank of the garment shown in Figs. 9 and 10, it will be seen that a triangular section at the upper portion of the normal symmetrical sleeve has been cut off, forming thereby a substantially narrow convexly curved shoulder end on said sleeve.

The dotted lines in Fig. 13 on the drawing show a normal symmetrical sleeve blank. The triangular pieces F^2 and R^2 are cut off therefrom to form the new sleeve as shown in the above figure in full lines.

40 By joining the adjacent sides of the front and back pattern blanks of the garment, I obtain the desired underarm fullness without recourse to extra seaming, tucking, piecing or gathering. It can be seen that by these simple means I obviate a number of operations in the manufacture of my garment and I obtain greater accuracy in fit and effect a cleaner and neater appearance.

Conversely, by extending either the front or 50 back blank members with a rectangular extension (Figs. 14 and 15) instead of extending both front and back members of the pattern blanks with lateral triangular extensions, I obtain also the aforementioned result, since thereby the lateral right angular extension Y^2 and X^2 (Fig. 14) in either of the front or back pattern blank members will provide sufficient fullness for both the front and back underarm portions of the garment.

55 In constructing my garment, I extend the front pattern, Fig. 14, approximately at the armpit R^2 and graduate with a concave curving the sides V^2 — O^2 .

60 A parallel and opposite concavely curved there- 65 to side edge is formed; said side edge beginning within the concave curve of a normal symmetrical armhole N^3 ; Fig. 14, and extended to M^3 ; Fig. 14. The two opposite side edges are next connected by a straight side edge M^3 ; O^3 ; and M^3 ; V^2 forming thereby rectangular lateral extensions Y^2 and X^2 shown in Fig. 14.

I join the respective side edges of the front and back blanks at O^2 — H^2 to A^3 — B^3 and the shoulder portion thereof at H^3 — I^3 to G^4 — F^3 . I use the 75 same sleeve construction shown in Fig. 13 and as

5

above described I join the opposite straight side edges of the sleeve blank, Fig. 13, D²—E² to D²—P² forming thereby a tubular sleeve.

The upper convex edge F²—Z²—Q⁴ I next secure to the upper armhole portion. The lateral extensions Y² and X³ I secure to the side edges of the sleeve F²—D², and Q⁴—D².

I have thus obtained the same results as shown in the sleeve and garment construction in Figs. 9 and 10, but instead of using lateral extensions on both front and back blank members of the garment, I use lateral right angle extensions as described.

Now, having described my invention, what I claim is:

1. In combination with a garment having front and back blanks defining an armhole opening, a sleeve formed of a single blank, said sleeve having a convexly curved upper portion, said front and back blanks having extended side portions, comprising substantially lateral triangular extensions on front and back portions of said blanks; said lateral triangular extensions having a concavely curved side end edge and an opposite concavely curved inner side end edge, said blank having a straight wrist end portion and an opposite thereto convexly curved shoulder end portion; said blank having intermediate straight sides connecting the convexly curved shoulder end edge of said sleeve to the wrist end of said sleeve, said intermediate sides of said sleeve blank being secured to the respective side edges of the lateral triangular extension of the front and back blanks and the convexly curved shoulder end of the sleeve blank being secured to the upper edges of said armhole opening.

2. In combination with a garment comprising front and back portions formed with arm hole openings, a sleeve member comprising a blank having a convexly curved upper edge and edges inclined outwardly of said curved edge, said front and back portions each including integral portions projecting outwardly of the lower portion of said armhole openings and formed with inner concave edges, said sleeve member having the inclined edges thereof stitched to said inner concave edges of the integral portions of said front and back portions and the curved edges of said sleeve member being stitched to upper edges of the armhole openings of said front and back portions.

3. A garment comprising a body portion having an armhole edge, said body portion comprising integral portions having converging concave edges

6

projecting upwardly from the lower portion of said armhole edge, a sleeve comprising a member having opposite edge portions seamed together and edges diverging from said seamed edges, said diverging edges being interconnected at their outer ends by a convex curved edge, said sleeve having its diverging edges stitched to the converging edges of said body portion and its curved edge stitched to the upper edges of the armhole opening in said body portion.

4. A garment comprising a body member having a front panel and a back panel, said panels being formed with armhole openings having concave curved edges, said panels comprising upwardly projecting integral portions having upper concave edges defined by the lower portion of said concave curved edges, the said integral portions extending outwardly of the side edges of said blanks and including lower edges extending upwardly and outwardly of said side edges, sleeve members stitched to said body member at said armhole openings, said sleeve members having inclined edges stitched to the upper edges of the integral portions on said panels.

5. A garment comprising a body member having front and back panels, said panels being formed with armhole openings, each of said panels comprising an integral portion projecting outwardly and upwardly of the side edges thereof, said projecting portions having inner concave edges and having their outer edges stitched together, a sleeve member having a curved edge stitched to a portion of the edge of said arm hole opening in said panels and edges inclined from said curved edge, said inclined edges being stitched to the inner edges of said projecting portions on said panels.
